UNITED STATES PATENT OFFICE.

WILLIAM S. WARD, OF PLANTSVILLE, CONNECTICUT, ASSIGNOR TO THE
H. D. SMITH & COMPANY, OF SAME PLACE.

DESIGN FOR A MEMBER FOR CARPENTERS' PINCERS.

SPECIFICATION forming part of Design No. 33,079, dated August 14, 1900.

Application filed July 19, 1900. Serial No. 24,226. Term of patent 14 years.

To all whom it may concern:

Be it known that I, WILLIAM S. WARD, a citizen of the United States, residing at Plantsville, in the county of Hartford and State of Connecticut, have invented and produced a new and original Design for a Member of a Carpenter's Pincers, of which the following is a specification, reference being had to the accompanying drawings, forming part thereof.

Figure 1 is a side elevation of one member of a carpenter's pincers, showing my design. Fig. 2 is a plan view of the same. Fig. 3 is a reverse side elevation of the same.

As shown in the drawings, the jaw A is mainly of the ordinary curved and hooked form or what may be called a "gooseneck" curve; but, unlike an ordinary gooseneck, there is a flat facet 4 on the back or outer convex portion of the jaw. Like a true gooseneck, the main portion of the outer edge of the jaw is curved transversely in addition to its general curvature in side view, whereby the facet 4 has substantially a round form, as seen in plan view in Fig. 2. The said facet

also materially modifies the contour of each pincer member, as seen in side view in Fig. 1. It may be noted that the facet 4 is not parallel to the length of the lever-handle 8, but slants forwardly, as seen in side view.

The sides 5 6 of the jaws are flat, and back of the jaws the members have a broad and rounded portion 7, that merges into the lever-handle 8, which handle gradually tapers toward the rear and is of a rounded oval form in cross-section. The handle-tip, which is shown in broken lines, is of an old and well-known form for the tips of pincer-handles and need not be specifically described.

Having described my invention, what I claim as new, and desire to secure by Letters Patent, is—

The design for a member of a carpenter's pincers, as herein shown and described.

WILLIAM S. WARD.
